CLAIM

The ornamental design for a display screen or portion thereof with graphical user interface, as shown and described.

DESCRIPTION

The FIGURE is a front view of a display screen or portion thereof with graphical user interface according to the claimed design.

The outermost broken lines illustrate a display screen or portion thereof and form no part of the claimed design. The remaining broken lines, including all text and icons, illustrate portions of the graphical user interface that form no part of the claimed design.

1 Claim, 1 Drawing Sheet
